United States Patent Office

Des. 188,320
Patented July 5, 1960

188,320

BUILDING BLOCK UNIT

Verne Frese, 7265 E. Marginal Way, Seattle, Wash.

Filed May 12, 1959, Ser. No. 55,879

Term of patent 14 years

(Cl. D18—2)

FIG. 1

FIG. 2

FIG. 3

FIG. 4

Fig. 1 is a front elevational view of a building block unit, showing my new design;

Fig. 2 is an end view as seen from the left of Fig. 1;

Fig. 3 is a bottom plan view of the block; and

Fig. 4 is a front perspective view thereof.

The dominant features of my design reside in the portions shown in full lines.

I claim:

The ornamental design for a building block unit, as shown and described.
